COMBINATION DISPLAY, STORAGE AND DISPENSING CABINET

Thomas Carvel, Winding Road Farms, Chauncey, N.Y.

Filed Apr. 28, 1964, Ser. No. 79,722

Term of patent 14 years

(Cl. D80—2)

FIG. 2

FIG. 1 is a front perspective view of a combination display, storage and dispensing cabinet showing my new design.

FIG. 2 is a rear perspective view thereof.

I claim:

The ornamental design for a combination display, storage and dispensing cabinet, as shown.
